POCKET CLIP FOR FISHING TACKLE

William S. Stowell, 1114 Bewley, Apt. 4,
Santa Ana, Calif. 92703

Filed June 1, 1973, Ser. No. 366,257

Term of patent 14 years

Int. Cl. D2—99

U.S. Cl. D2—400

FIG. 1 is a front perspective view of a pocket clip for fishing tackle showing my new design;

FIG. 2 is a back perspective view thereof; and

FIG. 3 is a cross sectional view on the line 3—3 of FIG. 1.

I claim:

The ornamental design for a pocket clip for fishing tackle, as shown.
